UNITED STATES PATENT OFFICE.

LOUIS MARX, OF NEW YORK, N. Y.

FIGURE WHEELED TOY.

Application filed September 28, 1923. Serial No. 665,284.

This invention relates to a toy, and relates more particularly to a mechanically operated figure toy; and has special reference to the provision of a toy in which a vehicle 5 combined with mechanically operable figures is adapted for propulsion along a support.

The principal objects of my present invention include the provision of a figure 10 toy in which a vehicle is combined with mechanically operable figures constructed so that when the combination is set into operation the vehicle and figures will be actuated to simulate coordinating vehicle propelling activity; the more specific provision 15 of a toy in which the vehicle simulates a child's coaster wagon and the figures are arranged fore and aft thereof in wagon pulling and pushing positions, the wagon and 20 figure ensemble being operable to uniquely simulate the propulsion of the vehicle by the pulling and pushing action of the figures; and the still further provision of a figure toy in which a vehicle in the form 25 of a child's wagon is combined with a mechanically operable figure arranged at the rear end thereof in sitting posture with mechanism provided for coordinately propelling the vehicle and operating the said 30 figure in life-like and natural semblance of a child moving a coaster wagon by pushing action.

Other and ancillary objects of the invention comprehend the provision of a mechanical figure toy made of few and simply co-ordinated parts producing a construction which is relatively strong, durable and inexpensive.

To the accomplishment of the foregoing 40 and such other objects as may hereinafter appear, my invention consists in the elements and their relation one to the other as hereinafter more particularly described and sought to be defined in the claims, reference being had to the accompanying drawings which show a preferred embodiment 45 of my invention, and in which:

Fig. 1 is a side elevational view of the figure toy showing the parts in one stage of 50 a cycle of operation, and

Fig. 2 is an elevational view thereof with parts in cross-section showing the same in a different stage of a cycle of operation.

Referring now more in detail to the drawings, the figure toy comprises generally a vehicle made preferably to simulate a child's

coaster wagon generally designated as W, a figure F at the front end of the vehicle arranged in position to simulate when operated a drawing or pulling of the vehicle, 60 a second figure F' arranged at the rear end of the wagon and preferably in sitting posture, positioned to simulate when operated a pushing activity of the wagon W, and a mechanism generally designated as M operable for propelling the vehicle along the ground or other supports and for causing the figures F and F' to simulate coordinating vehicle pulling and pushing action. 65

The wagon W may be made in any desirable shape or form, and may be conveniently constructed out of sheet metal, the said wagon including a body 10, a front wheel set 11 and a rear wheel set 12, the front wheel set being freely rotatable on a shaft 13 journalled in an inverted U-shaped frame 14 which may be swively connected as by means of the rivet 15 to the front of the wagon body 10, the rear wheel set 12 being preferably fixed to a shaft 16 70 journalled in the depending side brackets 75 17, the wagon further including the draft tongue 18 provided with the draw bar 19.

The front figure F desirably is made of sheet metal and comprises a hollow body 80 portion 20 having the fixed arms 21 extending rearwardly and attached to the draw bar 19, and oscillatably journalled on the body 10 there are provided the movable lower limbs 22 and 23 movable on the pivot pin 90 24, the limbs preferably comprising loosely jointed upper and lower members 22', 22² and 23', 23²; the construction being such that when the upper limb members 22', 23' 95 are oscillated, the lower limb members 22², 23² will be oscillated with an accentuated swinging motion so as to vividly simulate a rapid running motion of the figure. 100

The rear figure F' may also comprise a hollow body 25 provided with the arms 26, the 105 said body being arranged in sitting posture on the rear end of the vehicle, as clearly shown in the drawings, and oscillatably journalled on the body, as on the pivot pin 27, I provide the lower limbs 28 and 29 which also preferably comprise the loosely jointed upper and lower members 28', 28² and 29', 29², this so as to produce an accentuated swinging motion of the lower limb members when the upper members are oscillated. 110

The mechanism M desirably comprises a spring motor 30 having a winding key 31

and a holding ratchet 32, the motor being connected to a gear 33 which meshes with a pinion 34 fixed to a gear 35 and rotatable on a shaft 36, the gear 35 in turn meshing with a pinion 37 fixed to the rear wheel shaft or axle 16, the construction being such that when the spring motor is energized the gearing system will drive the rear wheel set 12 to propel the vehicle.

For operating the mechanical figure F' to produce a simulation of the wagon pushing action, the limb members 28' and 29' are oscillated by means of the rotation of the shaft or axle 16, and to this end the limb members 28' and 29' are provided with the extensions 37' and 37² defining arms to which are connected the connecting rods or pitmen 38' and 38², the lower ends of which are loosely connected to the opposed crank portions 39' and 39² which may conveniently be formed integrally with the shaft or axle 16. With this arrangement it will be obvious that when the vehicle is propelled the lower limbs of the figure F' will be oscillated in semblance of wagon pushing action.

In order to enhance the motion of the rear figure F', the construction further includes means whereby the body 25 of the rear figure is rocked to and fro as between the positions shown in Figs. 1 and 2 by the oscillation of the lower limbs, and to this end the lower part of the figure body 25 is provided with cut-away portions 40 (one of which is shown in the drawings), in which cut-away portions the limb members 28' and 29' are movable, the interengagement between these parts being, however, such that when the lower limbs are oscillated, the limb members 28' and 29' forcibly strike the body at the cut-away portions to impart to the same a to and fro rocking movement, the body being to this end pivoted on the pivot pin 27.

For actuating the lower limbs of the front figure F, the front axle or shaft 13 is also made in the form of a crank shaft provided with the oppositely arranged crank portions 41', 41² to which are connected the connecting rods or pitmen 42', 42², the connecting rods being in turn attached to the extensions or arms 43' and 43² formed integrally with the limb members 22' and 23'.

The operation of the figure toy will in the main be fully apparent from the above detailed description thereof. It will be apparent that upon energizing the spring motor the vehicle will be set in propelling motion and such motion will cause the actuation of the front and rear figures F and F' in coordinating natural semblance to wagon propelling activity, the front figure being actuated so as to simulate a rapid running and pulling motion, and the rear figure being coordinately operated to simulate an energetic wagon pushing motion.

While I have shown my device in the preferred form, it will be obvious that many changes and modifications may be made in the structure disclosed without departing from the spirit of the invention, defined in 70 the following claims.

I claim:

1. A wheeled toy for simulating a coordinated push and pull action comprising a wagon having front and rear sets of wheels, 75 a figure at the front end of the wagon arranged in wagon pulling relation and provided with oscillatable lower limbs, a figure at the rear end of the wagon arranged in wagon pushing relation and provided with 80 oscillatable lower limbs, motor mechanism on the wagon having a driving connection with one of the sets of wheels, and means connecting the front set of wheels with the limbs of the front figure and the rear set of 85 wheels with the limbs of the rear figure, whereby when the motor mechanism is operated to propel the wagon the front figure will be operated in simulation of wagon pulling 90 activity and the rear figure will be operated in simulation of wagon pushing activity.

2. A wheeled toy for simulating a coordinated push and pull action comprising a 95 draft vehicle, a figure at the front end of the vehicle arranged in vehicle pulling position and provided with movable lower limbs, a figure at the rear end of the vehicle arranged in vehicle pushing position and also provided with movable lower limbs, and motor mechanism carried by the vehicle for propelling the vehicle and connected to said figures for operating the limbs thereof for causing the front figure to simulate a pulling 100 and the rear figure a pushing activity.

3. A toy comprising a draft vehicle, a figure at the front end of the vehicle arranged in vehicle pulling position and provided with movable lower limbs, a figure at the rear end of the vehicle arranged in sitting posture on the vehicle and in vehicle pushing position 110 also provided with movable lower limbs, and mechanism carried by the vehicle for propelling the same and for operating the limbs of the figures to cause the front figure to simulate a pulling and the rear figure a pushing activity.

4. A wheeled toy for simulating a coordinated push and pull action comprising a wagon having front and rear sets of wheels, 115 a figure at the front end of the wagon arranged in wagon pulling relation and provided with loosely jointed oscillatable lower limbs, a figure at the rear end of the wagon arranged in wagon pushing relation and provided with loosely jointed oscillatable lower limbs, motor mechanism on the wagon having a driving connection with one of the sets of wheels, and means connecting the front 120 set of wheels with the thigh portions of the 125

130

limbs of the front figure and the rear set of wheels with the thigh portions of the limbs of the rear figure, whereby when the motor mechanism is operated to propel the wagon, 5 the figures will be operated in simulation of pushing and pulling wagon propelling activity.

5. A wheeled toy for simulating a coordinated push and pull action comprising a 10 wagon having front and rear sets of wheels, each set having a shaft forming a crank shaft, a figure at the front end of the wagon arranged in wagon pulling relation and provided with loosely jointed oscillatable lower 15 limbs, a figure at the rear end of the wagon arranged in sitting posture and in wagon pushing relation also provided with loosely jointed oscillatable lower limbs, motor mechanism on the wagon having a driving 20 connection with one of the sets of wheels, connecting rods connecting the lower limbs of the front figure with the crank shaft of the front wheel set, and connecting rods connecting the lower limbs of the rear figure 25 with the crank shaft of the rear wheel set whereby the first figure will be operated in

simulation of a pulling activity and the rear figure will be operated in simulation of a pushing activity.

6. A wheeled toy for simulating a coordinated push and pull action comprising a vehicle, a figure at the front end of the vehicle, arranged in vehicle pulling relation, a second figure arranged at the rear end of the vehicle in sitting posture thereon and arranged 30 in vehicle pushing relation, the second figure having a body mounted for to and fro rocking motion and having oscillatable lower limbs pivoted to the body and arranged so as to impart a rocking motion to the body 35 when oscillated, the first figure also including lower limbs, motor mechanism on the vehicle and means connecting the motor mechanism to the limbs of the figures whereby when the vehicle is propelled the limbs of 40 the figures and the body of the second figure are set into oscillation in simulation of 45 vehicle propelling activity.

Signed at New York city in the county of New York and State of New York, this 22nd 50 day of September, A. D. 1923.

LOUIS MARX.
